UNITED STATES PATENT OFFICE.

FRED A. POOR, OF CHICAGO, ILLINOIS, ASSIGNOR TO THE P. & M. COMPANY, OF CHICAGO, ILLINOIS, A CORPORATION OF ILLINOIS.

RAIL-ANCHOR.

1,292,873.

Specification of Letters Patent. Patented Jan. 28, 1919.

Application filed February 13, 1918. Serial No. 216,847.

To all whom it may concern:

Be it known that I, FRED A. POOR, a citizen of the United States, residing at Chicago, in the county of Cook and State of Illinois, have invented certain new and useful Improvements in Rail-Anchors, of which the following specification.

My invention relates to devices for preventing railroad rails from creeping longitudinally, and has for its primary object to provide an improved device of this type which will be simple in construction, inexpensive to manufacture, easily applied to the rail, and which will act to prevent the rail from creeping in either direction; an anti-creeping device having this latter characteristic being desirable for use on single track roads where the traffic runs in opposite directions, or in other situations in which the rail tends to move sometimes in one direction, and sometimes in the other.

The invention consists in the novel arrangements, constructions and combination of parts, hereinafter described and claimed, for carrying out the above stated object, and such other objects as may appear from the following specification.

The invention is illustrated in certain preferred embodiments in the accompanying drawings, wherein:

Figure 1 is a view in perspective of a rail anchor, constructed in accordance with my invention, applied to a railroad rail;

Fig. 2 is a plan view of the structure shown in Fig. 1;

Fig. 3 is a detail plan view of a spring member employed in my preferred construction;

Fig. 4 is a sectional view, on a reduced scale, taken on line 4-4 of Fig. 2;

Fig. 5 is a side view, in elevation, of a rail with my improved rail anchor applied in operative position thereto;

Fig. 6 is a view similar to Fig. 5 showing the spring member of my device in process of application to the rail.

Fig. 7 is a detail edge view of the spring member shown in the six preceding figures;

Fig. 8 is a view in perspective of another embodiment of my invention, illustrating a modified form of tie-engaging member;

Fig. 9 is a side view of the structure shown in Fig. 8;

Fig. 10 is a cross-section taken on line 10-10 of Fig. 9; and

Fig. 11 is a view in elevation, looking toward the inside of the tie-engaging member employed in the embodiment illustrated in Figs. 8, 9 and 10.

Like characters of reference designate like parts throughout the several figures of the drawings.

Referring first to Figs. 1 to 7 inclusive of the drawings, 10 designates a railroad rail and 11, 11^a two adjacent cross-ties on which the rail is supported. The rail anchor illustrated in these figures preferably consists of a shoe or rigid member 12, and a yoke member 13, which together embrace the base flange of the rail and have an interlocking engagement with each other which maintains these members in their operative position on the rail. The shoe member 12 may be made of any suitable material; preferably it is a malleable casting, and is formed with jaws 14, 14^a which fit over one edge of the rail base at points adjacent the cross-ties 11, 11^a, respectively. These jaws are preferably made up of an upper lip 15, which preferably extends the entire length of the shoe and has its under surface 16 formed with an inclination which corresponds to the taper of the upper surface of the rail base, and with lower lips 17 and 18 at each end of the shoe which extend under the rail base and engage the under surface thereof. A vertical web 19 connects the above mentioned lips together and rigidifies the shoe 12 as a whole from end to end. 20, 20^a designate tie abutting portions formed at each end of the shoe 12 and which are adapted to bear against the adjacent vertical faces of the cross-ties 11, 11^a, respectively. The vertical web 19 is preferably curved downwardly as indicated at 21, so as to reinforce the lower portion of the tie abutting portions 20, 20^a. The yoke 13 is preferably made of spring metal and is formed at one end with a jaw 22 which engages the edge of the rail base opposite the shoe 12, and is formed with an angularly disposed hook portion 23, which is forced into a biting engagement with the upper surface of the rail base when the anchor device is applied to the rail and is in its operative position. The spring yoke 13 is formed at the other end with an enlargement 24 which extends around the shoe 12 and interlocks therewith in a manner hereinafter described. The portion of the yoke which extends under the rail is preferably 110

given a slight set or twist, as indicated in Figs. 3 and 7, so that the enlargement 24 will normally stand at a slight angle with relation to the jaw 22. When the shoe 12 and the yoke 13 are in operative position on the rail, the body portion of the yoke adjacent the enlargement 24 extends into a recess 25 formed in the web 19 (Figs. 5 and 6). 26 designates a projection on the web 19 which is cut away as indicated at 26^a to provide a supporting shelf adapted to support the lower edge of the yoke. When applying the yoke 13 to its interlocking position with the shoe 12, as indicated in Figs. 1, 2, 4 and 5, the yoke is subjected to a torsional strain by twisting the same from its normal set position, as indicated in Fig. 3, to the position indicated in Figs. 1 and 2. This twisting operation may be accomplished by any suitable means, such for example, by use of the claw bar or wrench 28 (Fig. 6), which may be applied over the enlargement 24. 29 designates a boss on the wrench which engages the projection 26 and provides a suitable fulcrum for the wrench when springing the yoke from its normal position, as indicated in Fig. 6, to its operative position, as indicated in Fig. 5. The yoke 13, in addition to being twisted, is raised so that when in operative position the upper end of the enlargement 24 will extend back of a lug 30 formed on the shoe. By straining the yoke 13 in this manner, the jaw end of the yoke is rocked rearwardly, so that the angularly disposed lip 23 of the jaw 22 will exert a downward pressure against the upper surface of the rail base.

The tendency which the spring yoke has to return to its normal, or twisted condition exerts a spring pressure against the lug 30. This pressure prevents vibration of the rail from dislodging the yoke from its seat on the shelf 26^a, or appreciably lessening its effective grip on the base flange of the rail. 45 The spring yoke, when applied in operative position, preferably stands at substantially right angles to the shoe 12, so that any longitudinal movement of the rail in either direction tending to change the angular relation of these members will increase the grip of the device on the rail base.

In the embodiment of the invention illustrated in Figs. 8 to 11 inclusive, I have shown a modified form of shoe or rigid member 31 which consists of a metal bar which engages the upper inclined surface of the base flange A of the rail base, and is formed at each end with tie engaging lugs 32, 32^a. These lugs are preferably formed with 60 shoulders which fit over the vertical edge of the base flange of the rail and are spiked to the top surface of two adjacent ties by means of spikes 33. The bar 31 is provided at the center with a depending flange 34 which is recessed as indicated at 35 to receive the

body portion of the spring yoke, and is provided with a supporting shelf 36 and boss 37 for holding the spring yoke member 13^a in its operative position, in substantially the same manner as that described in connection with the device shown in Figs. 1 to 7 inclusive. The web 34 is formed on each side of the recess 35 with inwardly projecting lugs 38 and 39, which extend underneath the rail base and provide a rail base engaging jaw 40 adjacent the spring yoke 13^a. In other respects, the construction and operation of this device is substantially the same as the device shown in Figs. 1 to 7 inclusive.

While I have shown and described my invention in two specific embodiments, it will be obvious that further structural modifications might be made without departure from this invention. I therefore do not wish to limit myself to the exact structure shown and described, except so far as specific limitations may appear in the appended claims.

I claim:

1. A rail anchor adapted to resist longitudinal movement of a rail in either direction, comprising a rigid member and a spring member having an interlocking engagement with each other and which together embrace the base of the rail.

2. A rail anchor adapted to resist longitudinal movement of a rail in either direction, comprising a rigid member and a spring member having an interlocking engagement with each other and which together embrace the base of the rail, said rigid member extending from one of the ties on which the rail is supported to the next adjacent tie.

3. A rail anchor comprising a shoe member and a spring member provided with jaws adapted to engage opposite edges of the base flange of a rail, one of said members being adapted to engage adjacent ties to resist longitudinal movement of the rail in either direction.

4. A rail anchor comprising a shoe member and a spring member provided with jaws adapted to engage opposite edges of the base flange of a rail, one of said members being formed with tie abutting portions adapted to engage adjacent ties.

5. A rail anchor comprising a shoe member and a spring member provided with jaws adapted to engage opposite edges of the base flange of a rail, one of said members being formed with tie abutting portions adapted to engage the vertical sides of adjacent ties.

6. A rail anchor comprising a shoe member which fits over one edge of a rail base and is adapted to engage two adjacent ties, and a spring member engaging the opposite edge of the rail base and having an interlocking engagement with the shoe member.

7. A rail anchor comprising a shoe mem-

ber formed with a jaw which fits over one edge of a rail base and is adapted to engage two adjacent ties, and a spring member engaging the opposite edge of the rail base and having an interlocking engagement with the shoe member.

8. A rail anchor comprising a shoe member formed with a jaw at each end which fits over one edge of a rail base and is adapted 10 to engage two adjacent ties, and a spring member engaging the opposite edge of the rail base and having an interlocking engagement with the shoe member.

9. A rail anchor comprising a rigid member engaging two adjacent ties and formed 15 with spaced jaws which fit over one edge of the base of a rail, and a spring member engaging the opposite edge of said rail base and having an interlocking engagement 20 with said rigid member, said spring member being adapted to be strained in its application to the rail.

10. A rail anchor comprising a rigid member engaging two adjacent ties and formed with spaced jaws which fit over one edge 25 of the base of a rail, and a spring member engaging the opposite edge of said rail base and having an interlocking engagement with said rigid member, said spring member being subjected to a torsional strain in 30 its application to the rail.

11. A rail anchor comprising a rigid member formed with a rail base engaging jaw and with tie abutting portions adapted to bear against the vertical faces of two adjacent ties, and a spring yoke formed with a jaw which engages the opposite edge of the rail base and with an enlargement having an interlocking engagement with said rigid member; said spring yoke being subjected to a torsional strain when applied to 35 40 the rail.

FRED A. POOR.
